UNITED STATES PATENT OFFICE.

ANNIE W. HALSTEAD, OF KESLERS CROSS LANES, WEST VIRGINIA.

BATH-BRUSH.

1,064,641.

Specification of Letters Patent. Patented June 10, 1913.

Application filed January 22, 1913. Serial No. 743,610.

To all whom it may concern:

Be it known that I, ANNIE W. HALSTEAD, a citizen of the United States, residing at Keslers Cross Lanes, in the county of Nicholas and State of West Virginia, have invented a new and useful Bath-Brush, of which the following is a specification.

My invention relates to new and useful improvements in a bath brush, and more particularly to a fountain bath brush.

The object of the invention is the provision of a brush of this character which is flexible and will fit the hand and which will hold the water or other liquid used until the brush is applied.

A further object of the invention is the provision of means for preventing the water or other liquid from splashing when in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

Figure 1 is a perspective view. Fig. 2 is a partial transverse sectional view showing parts when not in use, and Fig. 3 is a partial transverse sectional view showing the parts when in use.

In constructing my brush I provide a hollow body portion which comprises a top 1, a bottom 2 and the sides 3. As clearly shown in Figs. 2 and 3 of the drawing the sides 3 are of greater thickness than the top and bottom in order to support the top from the bottom. The body is formed of flexible material, preferably rubber and formed integral with the bottom are the perforated teeth 4 of such construction that the perforations will be closed when the brush is not in use as shown in Fig. 2 and which will open when the brush is applied to the body, as shown in Fig. 3. Secured to the bottom

of the body is a flange member 5 which I preferably form of sponge rubber. This flange is of the same thickness as the length 50 of the teeth and will prevent the water or other liquid from splashing when the brush is being used.

An opening is formed in the top of the brush for filling the same and is closed by 55 the cap 6. I also provide the straps 7 for securing the brush to the hand and the ends of the strap are secured by the fastener 8 as shown in Fig. 1.

It will be seen that the brush being formed 60 of flexible material will conform to the shape of the hand when in use and by placing the opening for filling in the center of the brush it will not interfere in any manner with the brush conforming to the hand. 65 As above described the teeth are closed when the brush is not in use but when the brush is applied to the body the pressure on the top of the teeth and from the bottom thereof, will open the same and allow the liquid to 70 pass through the teeth. The flange 5 being formed of sponge rubber, will conform to the curvature of the body of the brush and contact with the body when the brush is in use and thereby prevent the water from 75 splashing from the brush.

Having fully described my invention what I claim and desire to secure by Letters Patent is:

A bath brush comprising a hollow flexible 80 body, the sides of which are of greater thickness than the top and bottom, perforated flexible teeth leading from the body, said teeth being normally closed and opened by pressure thereon, and a flange secured to the 85 body and encircling the teeth.

In testimony that I claim the foregoing as my own, I have hereto affixed my signature in the presence of two witnesses.

ANNIE W. HALSTEAD.
